UNITED STATES PATENT OFFICE.

ROBERT LEE McCOURBIE, OF PHILADELPHIA, PENNSYLVANIA.

CLOTHES-WRINGER ATTACHMENT.

Application filed March 18, 1926. Serial No. 95,608.

This invention relates to an attachment for clothes wringers whereby the clothes may be guided and fed into the rolls without endangering the hands of the operator.

5 The principal object of the invention is the provision of means by which the washed clothes of any bulk may be readily and safely guided and pushed to the wringer so as to be positively gripped by the rolls without 10 making it necessary for the hands or fingers of the operator coming into proximity thereto.

Another important object of the invention is the provision of guide tables which are so 15 adjustable as to serve both as a guide to clothes entering the rolls, and for water running from the rolls, the tables being adjustable and interchangeable.

To this end the invention contemplates the 20 attachment to a clothes wringer of the usual type of two pairs of brackets, one on each side of the rolls, and to the wringer frame so as to support on one side of the wringer a table in substantially horizontal position and 25 approximately at or just below the meeting faces of the rolls. This table is provided to support the clothes being fed to the wringer. A pusher device straddles this table and is free to move both toward and away 30 from the rolls and also vertically away from the table. The operator feeds the clothes by means of the pusher toward the rolls where they are gripped and the water squeezed therefrom.

35 At the other side of the wringer rolls is a like pair of brackets supporting a similar table except that it occupies a position beneath the rolls and inclined downwardly so as to catch and direct the water dropping 40 from the rolls into a tub or other receptacle and yet in such a position as not to interfere with the wrung or dry clothes.

The invention further consists in the novel arrangement, combination and construction 45 of parts hereafter described and shown in the drawings.

In these drawings:—

Fig. 1 is a side elevation of one embodiment of my invention.

50 Fig. 2 is a plan view of Fig. 1.

Fig. 3 is an enlarged detail of the table supporting mechanism along the line 3—3 of Fig. 1.

Fig. 4 is a detail of the table.

55 Fig. 5 is a fragmentary plan view of the table.

Fig. 6 is a sectional view along the lines 6—6 of Fig. 5.

Fig. 7 is an end elevation of the clothes feeding device.

Fig. 8 is a fragmentary front elevation of the device of Fig. 7.

Fig. 9 is a fragmentary sectional view of the water receiving chute.

Referring now to the embodiment shown, 1 65 represents a wringer frame in which rolls 2 are journaled in the ordinary manner and to which no claim is made.

Secured to the frame 1 is a pair of brackets 3 and 4 of approximately triangular configuration, the upper edge of which occupies a substantially horizontal position. The upper corner of these brackets near the wringer rolls 2 is provided with a ledge or seat 5.

A table is provided having a supporting 70 surface 6 and having raised edges 7 to keep the clothes fed to the rolls from sliding therefrom and acting as a guide therefor. Beneath one longitudinal edge of the table I provide brackets 8 which slidably support

75 stub rods 9. One end of each rod rides in an angular slot 11 in table supporting brackets 3 and 4, and each rod is provided with a collar 12 held on said rod by a pin 13. A coil spring 14 encircling the rod 9 is placed 80 between a bracket 8 and a collar 12. The spring being under compression, pushes against collar 12 which keeps rod 9 in the hole 9^a near end of slot 11. Lugs 15 attached to rods 9 may be grasped by the operator and when made to approach each other, rods 9 are drawn out of holes 9^a so 85 that the rods may be moved in slots 11.

It will thus be noted that a table 6 may 90 be supported at the feed side of a wringing machine at its front longitudinal edge by rods 9 seated at their ends in the holes 9^a close to the ends of the slots 11 in brackets 3 and 4 and at its corners opposite said edge on 95 seats 5. In this position clothes to be wrung 100 out may be placed and fed as desired. Inasmuch as that edge of the table 6 nearest the rolls 2 may be readily moved upward, no undesirable consequences such as tearing the clothes will result should they wrap around the lower roll and approach the roll junction from beneath the table.

I have found a convenient and satisfactory device for feeding the clothes to consist of a pusher element 16 having guides 110 17 secured to its edges in such a manner that the pusher extends upward in prefer-

ably an inclined position. The pusher 16 may be provided with a hand grip or hold as at 18 for the convenience of the operator. The guides 17 extend downwardly through a space between the lateral edge of the table 6, and the brackets 3 and 4. These guides are preferably of considerable extent so as to accommodate clothes of varying bulk without causing the guides to leave their slots.

10 It is to be noted that the pusher rests on the table by its own weight so that clothes gripped by the rolls may be pulled beneath the pusher moving that member readily upward even without attention of the operator.

15 A foot 19 is provided at each side of the pusher in order to assist in holding the device upright.

On that side of the wringer from which the dried clothes are normally ejected, I 20 provide a pair of brackets and a table identical in all respects to these parts already described. The table 20, however, on this side of the machine, occupies a position directly beneath the rolls 2, but out of the way of clothes being ejected therefrom. The table 25 20 is made to assume this position by causing the lugs 15 to approach each other, thus drawing rods out of hole 9^a and allowing them to ride in the slot, and then pushing

30 the table toward the wringer until the ends of the rods 9 occupy a position at the farthest end of the slots 11. In this position, the opposite longitudinal edge of the table 20 rests on the chute 21 usually provided in

35 wringing machines. In this position it will be seen that water dripping from the rolls 2 will be caught by the table 20 and directed into a tub or other receptacle placed beneath the appropriate chute 21, a clothes basket 40 22 catching the clothes from the other chute.

The part 4 of the bracket is made somewhat thicker than the web 3 and the hole 9^a is made in this thickened portion into which the ends of the rods 9 are socketed.

In order to pivot the table downwardly 45 past the supporting ledges 5 the handles 15 are made to approach each other whereupon the entire table may be removed backwards toward the operator sufficiently to have the forward edges of the table clear the ledges 5. 50

Obviously either table may be made to occupy any position intermediate the positions shown, by proper manipulation of the lugs 15.

Having thus described my invention, what 55 I claim is:—

1. In combination, a clothes wringer having rolls, a clothes supporting table at approximately the level of the rolls, and means to feed clothes while supported on said table 60 comprising a pusher element having guides straddling said table.

2. In combination, a clothes wringer having rolls, a clothes supporting table at approximately the level of the rolls, and means 65 to feed clothes while supported on said table comprising a pusher element having guides straddling said table, and capable of free vertical movement.

3. In combination, a clothes wringer having rolls, a clothes supporting table therefor, brackets at each side of the table, a ledge in proximity to said rolls, that longitudinal edge of the table nearest the rolls resting by gravity on said ledge, the table being pivotally supported in said brackets at the opposite edge. 70 75

In testimony whereof, I affix my signature.

ROBERT LEE McCoubrie.
